US0D1004618S

(12) **United States Design Patent** (10) Patent No.: **US D1,004,618 S**
(45) Date of Patent: ** Nov. 14, 2023

- (54) **ELECTRONIC DEVICE WITH GRAPHICAL USER INTERFACE HAVING A THREE-DIMENSIONAL APPEARANCE**
- (71) Applicant: **Apple Inc.**, Cupertino, CA (US)
- (72) Inventors: **Guillaume P. Barlier**, San Mateo, CA (US); **Lisa K. Forssell**, Palo Alto, CA (US); **Joseph D. Gardner**, San Francisco, CA (US); **Aurelio Guzmán**, San Jose, CA (US); **Jason D. Rickwald**, Santa Cruz, CA (US); **Christopher J. Romney**, San Francisco, CA (US); **Nicolas V. Scapell**, London (GB); **Christopher I. Wilson**, San Francisco, CA (US)
- (73) Assignee: **Apple Inc.**, Cupertino, CA (US)
- (**) Term: **15 Years**
- (21) Appl. No.: **29/864,897**
- (22) Filed: **Jun. 27, 2022**

CLAIM

The ornamental design for an electronic device with graphical user interface having a three-dimensional appearance, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface having a three-dimensional appearance showing the claimed design;

FIG. 2 is another front view thereof, showing the front orientation of the graphical user interface;

FIG. 3 is another front view thereof, showing the rear orientation of the graphical user interface;

FIG. 4 is another front view thereof, showing the right side orientation of the graphical user interface;

FIG. 5 is another front view thereof, showing the left side orientation of the graphical user interface;

FIG. 6 is another front view thereof, showing the top orientation of the graphical user interface;

FIG. 7 is another front view thereof, showing the bottom orientation of the graphical user interface; and,

FIG. 8 is a front view of an electronic device having a display screen with the graphical user interface of FIG. 1 applied to the display screen. The graphical user interface designs of FIGS. 2-7 may be similarly applied thereto.

The outer broken lines in the figures show a display screen or portion thereof, or an electronic device having a display screen, and form no part of the claimed design. The other broken lines in FIG. 8 show portions that form no part of the claimed design.

The graphical user interface in FIGS. 1-8 is shown in various orientations to provide an understanding of the three-dimensional appearance of the design. The scope of the claim does not include any orientation or view that is not shown.
